Primary Examiner — Amy C Wierenga*Assistant Examiner* — Grace Doyle(74) *Attorney, Agent, or Firm* — McCarter & English, LLP; Dave S. Christensen(57) **CLAIM**

The ornamental design for a jewelry clasp as shown and described.

DESCRIPTION

FIG. 1 is a perspective view of a jewelry clasp embodying my new design.

FIG. 2 is a front view thereof.

FIG. 3 is a rear view thereof.

FIG. 4 is a top view thereof.

FIG. 5 is a bottom view thereof.

FIG. 6 is a right side view thereof; and,

FIG. 7 is a left side view thereof.

The broken line(s) shown in the drawings illustrate portions of the jewelry clasp that form no part of the claimed design.

1 Claim, 2 Drawing Sheets(56)
